UNITED STATES PATENT OFFICE.

JARVIS B. EDSON, OF ADAMS, MASSACHUSETTS.

TREATING MATERIAL WITH ZYLONITE TO RESEMBLE PEBBLE, GOAT, FRENCH CALF, AND ALLIGATOR LEATHER.

SPECIFICATION forming part of Letters Patent No. 289,338, dated November 27, 1883.
Application filed October 12, 1883. (No specimen)

To all whom it may concern:

Be it known that I, JARVIS B. EDSON, a citizen of the United States, residing at Adams, Berkshire county, Massachusetts, have invented new and useful Improvements in Treating Material with Zylonite to Resemble Pebble, Goat, French Calf, and Alligator Leather, of which the following is a specification.

This invention has for its object the production of an article which resembles leather having the finish of pebble-goat, French calf, or alligator, and possesses properties superior to those existing in the substances known by the above terms; and the invention consists in taking sheets of leather such as are technically called "splits," or those which have been subjected to the splitting process, and applying upon the surface of the same thin sheets of zylonite or a similar pyroxyline substance of a proper color, and which is applied by partially dissolving the surface of the zylonite or its equivalent by any of the well-known solvents of such substances, and then subjecting the same to pressure—as by a pair of rolls or any gradually progressing compressing-surface—so that a split or side of leather, say, three feet wide and six in length, will be under pressure for a period of, say, five minutes, or thereabout, to produce a goat pebble, or a period of, say, a quarter of a minute to produce a French calf, or a period of, say, ten or fifteen minutes to produce an alligator-surface, by which pressure the leather and the zylonite will be united, and then partially dissolving or applying a solvent—such as collodion—upon the exterior surface of the sheet of zylonite, and progressively passing it between a pair of rolls or compressing-surface under a pressure of two hundred pounds, more or less, and moved at a speed of about ten feet per minute (more or less) in contact with a plate of glass or other similar surface, by which the exterior surface of the zylonite will be as finely polished as the surface against which it has been compressed. A convex surface, beginning at the center of the split and gradually extending out to each end in the case of such articles as are formed from sides of leather, will be found to be the preferable method of applying

the pressure, owing to the difficulty in forming a whole skin into a plane. In extremely troublesome cases the puckery or wrinkled parts may be placed under tension, as skins are stretched in frames in tanning processes, and, being so held flat, readily combined with the thin zylonite or similar pyroxyline compound. The convex surface to be used in these cases will be an elastic or compressible one, such as rubber or its equivalent. The polishing or glossing of the resulting surface may be effected simultaneously with the combining operation, or before or after the same, depending upon the nature of the surface to be operated upon and the degree of polish or gloss required. In some cases a simple treatment with a fluid solvent, removing quickly the surplus, will, with a warm temperature, render a satisfactory gloss. Whatever the result desired, it will be necessary in all cases to so operate as to prevent the solvent used for combining from being in excess or too long in contact with the thin sheet before placing in contact with the leather or base. I therefore prefer applying the solvent gradually or progressively, and then in same manner almost immediately perform the pressing and combining operation, and thereby simultaneously expelling the surplus solvent.

Having thus described my invention, what I claim is—

1. The method of making a substitute for leather resembling goat pebble, French calf, or alligator, consisting in partially dissolving the surface of a sheet of zylonite or similar pyroxyline substance by a suitable solvent; secondly, applying the said sheet to the material forming the base with the partially-dissolved side of the sheet next thereto; and, thirdly, applying pressure for a period of time sufficient to imitate the kind of leather to be produced, and to expel the surplus solvent and air and cause an intimate union of the base and sheet of zylonite, substantially as described.

2. The method of making a substitute for leather resembling goat pebble, French calf, or alligator, consisting in partially dissolving the surface of a sheet of zylonite or similar pyroxyline substance; secondly, uniting said

partially dissolved surface of the material forming the base by pressure sufficient to imitate the kind of leather to be produced, then partially dissolving the exterior surface of the sheet of zylonite and compressing the partially dissolved surface next to a material having a highly-polished surface, substantially as described.

3. As a new article of manufacture, a substitute for goat pebble, French calf, or alligator leather, consisting of a suitable base-forming material having attached to one of its

surfaces a thin sheet of zylonite or similar pyroxyline material having a polished surface in imitation of the leather mentioned, substantially as described.

In testimony whereof I have hereunto set my hand in the presence of two subscribing witnesses.

JARVIS B. EDSON.
